UNITED STATES PATENT OFFICE.

CHARLES W. THOMPSON, OF KALAMAZOO, MICHIGAN.

COMBINATION HOSE-SUPPORTER AND SUSPENDERS.

SPECIFICATION forming part of Letters Patent No. 764,080, dated July 5, 1904.

Application filed February 12, 1904. Serial No. 193,239. (No model.)

To all whom it may concern:

Be it known that I, CHARLES W. THOMPSON, a citizen of the United States, residing at the city of Kalamazoo, county of Kalamazoo, and 5 State of Michigan, have invented certain new and useful Improvements in Combination Hose-Supporters and Suspenders, of which the following is a specification.

This invention relates to improvements in 10 combination hose-supporters and suspenders.

The objects of the invention are, first, to provide an improved combination hose-supporter and suspender which is simple and economical to construct and convenient to 15 use; second, to provide an improved combination hose-supporter and suspender which effectively supports the garments and one by which dressing and undressing are greatly facilitated; third, to provide an improved 20 hose-supporter which in use is always retained in proper position on the person of the wearer and one by which the weight of the garments is properly distributed, so that it is borne by the parts of the body least likely to 25 be injuriously affected thereby.

Further objects and objects relating to structural details will definitely appear from the detailed description to follow.

I accomplish the objects of my invention 30 by the devices and means described in the following specification.

The invention is clearly defined and pointed out in the claims.

A structure embodying the features of my 35 invention is clearly illustrated in the accompanying drawing, in which the view is a front elevation of my improved combination hose-supporter and suspender.

In the drawing similar letters of reference 40 refer to similar parts.

Referring to the drawing, the supporting or shoulder straps A are secured together at the back in a manner similar to that of a pair of suspenders. Hose-gripping devices 45 D are detachably secured to the front ends of these supporting or shoulder straps A by cast-off clasps or buckles d. Suitable adjusting-buckles a are provided for the straps A. On the back the shoulder-straps A are ex- 50 tended at A' beyond the point of crossing.

These extensions A' are of such length that they reach downwardly and forwardly around the person, so that they reach the front straps A below the waist-line, when such straps A are in substantially a perpendicular position 55 down from the shoulder to the front of the thigh. This arrangement of the front straps brings the hose-supporting straps D square in front of the thigh, and the clasps being arranged each side serve to keep the supporter 60 in the best possible position and to prevent unnecessary strain upon the same or on the person of the wearer. By the arrangement of the straps in this way it will further be observed that the burden of carrying the garments is distributed on the shoulder, across 65 the back, and over the hips of the wearer, so that no discomfort will arise from unnecessary pressure at any point.

Suitable suspender-ends or trouser-supports 70 B and C are provided. The suspender-ends C are provided with slide suspender-buckles C', which are adapted to be adjusted on the shoulder or supporting straps A. These buckles are preferably the detachable style 75 illustrated, although other styles may be used with satisfactory results.

The structure illustrated is designed particularly for boys, and avoids the necessity of securing the trousers to the waist or providing 80 a waist for that purpose. At the same time the trousers are comfortably supported and the weight of the garment is properly distributed on the person of the wearer. By using the cast-off clasps or buckles d for securing 85 the hose grips or supports to the supporting or shoulder straps much time is saved in dressing and undressing, and a child using the same can adjust and secure the parts together.

It is evident that the device is adapted to 90 women's use as a hose-supporter only by eliminating the suspender-ends.

As before remarked, by the arrangement of the parts described the structure is always retained in the proper position on the person of 95 the wearer and the weight is distributed on the shoulders, back, and hips. Its convenience in the matter of the adjustment and use is apparent.

I have illustrated and described my im- 100

proved combined hose - supporter and suspender in the form preferred by me on account of its structural simplicity and economy of manufacture and convenience in use. I am, 5 however, aware that it is capable of considerable structural variation without departing from my invention.

Having thus described my invention, what I claim as new, and desire to secure by Letters 10 Patent, is—

1. In an article of the class described, the combination of shoulder-straps secured together at the back; extensions thereon, passed downwardly and forwardly around the person 15 of the wearer and secured to the front end of said shoulder-straps when such straps are arranged in substantially a perpendicular position; suitable hose-supporting devices secured to the front ends of said shoulder-straps 20 by cast-off clasps or buckles; suitable front and rear suspender-ends; and detachable slide-buckles for securing said front suspender-ends directly to said shoulder-straps, substantially as described.

2. In an article of the class described, the combination of shoulder-straps secured to-

gether at the rear; extensions thereon, passed downwardly and forwardly around the person of the wearer, and secured to the front ends of said shoulder-straps when such straps are 30 arranged in substantially a perpendicular position; suitable hose-supporting devices secured to the front ends of said shoulder-straps; and suitable suspender-ends, substantially as described.

3. In an article of the class described, the combination of shoulder-straps secured together at the rear; extensions thereon, passed downwardly and forwardly around the person of the wearer, and secured to the front ends 40 of said shoulder-straps when such straps are arranged in substantially a perpendicular position; and suitable hose-supporting devices secured to the front ends of said shoulder-straps, substantially as described.

In witness whereof I have hereunto set my hand in the presence of two witnesses.

CHARLES W. THOMPSON.
